UNITED STATES PATENT OFFICE.

WILLIAM N. ALLAN, OF SAN ANTONIO, TEXAS.

DESIGN FOR A TREAD FOR A VEHICLE TIRE.

60,596.

Specification for Design.

Patented Mar. 14, 1922.

Application filed August 27, 1920. Serial No. 406,487. Term of patent 3½ years.

To all whom it may concern:

Be it known that I, WILLIAM N. ALLAN, a citizen of the United States, residing at San Antonio, in the county of Bexar and State of Texas, have invented a new, original, and ornamental Design for a Tread for a Vehicle Tire, of which the following is a specification, reference being had to the accom-

panying drawing, forming part thereof, in which the figure is a plan view of the tread of a vehicle tire, showing my new design.

I claim:

The ornamental design for a tread for a vehicle tire, as shown.

WILLIAM N. ALLAN.
